UNITED STATES PATENT OFFICE.

HARRY L. HUSSMANN, OF ST. LOUIS, MISSOURI, ASSIGNOR TO HARRY L. HUSSMANN REFRIGERATOR & SUPPLY COMPANY, OF ST. LOUIS, MISSOURI, A CORPORATION OF MISSOURI.

SHOWCASE REFRIGERATOR.

Application filed March 1, 1922. Serial No. 540,313.

To all whom it may concern:

Be it known that I, HARRY L. HUSSMANN, a citizen of the United States, and residing at St. Louis, Missouri, have invented the new and useful Improvement in Showcase Refrigerators, of which the following is a specification.

This invention relates to refrigerators, and more particularly to show case refrigerators, such as shown and described in Patent No. 1,225,682, patented May 8, 1917 and in my application Serial Number 463,250, filed April 21, 1921.

In this type of refrigerator a compartment is provided for the refrigerant or freezing mixture container and a side door is provided through which said container may be removed. It has been found in practice that considerable moisture condenses on the interior surface of the door and walls on the adjacent side of the container and the drip pan. This is due to the fact that the refrigerant or freezing mixture container has a metallic wall which is opposite but close to the door, and that this container is constructed and positioned to cause circulation of air between the wall and the door and also in and around the drip pan positioned between the wall and the door. This circulating air from the show case compartment, of course, contains considerable moisture, which will condense on the extremely cold metal wall of the container and upon the metal pan and the inside door face close to the container wall and in the path of the circulating air. The moisture, after trickling down the interior surface of the door, may drip upon the sill and will sometimes creep along the sill to the outside of the refrigerator and leak through the door opening.

One of the objects of this invention, therefore, is to provide means whereby such leakage of the water of condensation through the door opening may be prevented.

Another object of this invention is to provide means for draining the drip water from the door sill to the inside of the compartment so as to prevent lodgement of the water on the door sill and the consequent rotting of the sill.

Another object of this invention is to provide a pan mounted and arranged for catching the drip from the container when the latter is moved out of the refrigerator.

Further objects will appear from the detail description taken in connection with the accompanying drawing, in which:

Figure 1 is a sectional view taken at the refrigerant container compartment, showing a refrigerator embodying this invention;

Figure 2 is a detail view showing the means of securing the drip pan in raised position;

Figure 3 is a detail showing the construction of the hinge of the drip pan, the shape of the sill, and the drip edge on the door; and

Figures 4 and 5 are details of the hinge construction for the drip pan.

Referring to the accompanying drawing, 1 designates the refrigerator casing within which is a compartment 2 for the refrigerant container 3, from which the drippings fall. These may be of the construction described and illustrated in the above-mentioned patent and application. The container 3 is provided with rollers 4 adapted to run on tracks 5, suitably supported within the compartment 2 and extending to the door opening. The door 6 is hinged to open sideways to allow the removal of the container. Hinged to the track 5 near the end thereof is a drip pan 7. The pan 7 is provided with up-turned flanges on three sides thereof so as to retain the drip water. The fourth side is provided with an extension 8 adapted to extend within the door-way when the pan is lowered, so as to discharge or drain the drippings within the compartment 2. The pan 7 is reinforced at the edges thereof by a pair of rails 9, (only one of which is shown), adapted to reinforce the pan. A cleat 10 is fixed to each of the rails 9 and extends beyond the end of said rail, being hinged at 11 to the track 5. This provides a hinge upon which the pan 7 may be lowered when it is desired to remove the container 3, the container being run out over the pan directly therebeneath in order that the latter may catch the drippings therefrom, which drain into the compartment. When in lowered position the pan may be additionally supported by a toggle 12 suitably hinged to the pan 7 at one end and to the refrigerator casing at the other. The pan may thus be folded on the hinge 11 into the door-way and to a position within the compartment 2 alongside of and against the container 3, as illustrated in Figure 1,

110

in which position it may be secured by an arm 13 engaging a recess 14 in the casing.

The inner wall of the door 6 extends over a sill 15 formed on the lower casing wall.

- 5 This sill is provided with a curved or sloping-surface sloping downwardly toward the interior of the compartment 2 so that water dripping thereon may flow inwardly into said compartment. The surface of the sill 10 may be protected by a covering 16 which may be of galvanized iron or similar material adapted to resist corrosion. Along the lower inner edge of the door 6 a groove 17 is provided so as to form a drip edge 18 15 along the inner edge of the door, the groove 17 acting to prevent the water of condensation from creeping along the under surface of the door toward the outside of the casing. The door may also be provided 20 with a weather strip 19 adapted to more effectively seal the door opening.

It will, therefore, be seen that by this construction all leakage of the condensation water to the outside of the refrigerator casing 25 may be prevented. The water resulting from the moisture present in the circulating air coming from the show case compartment condensing on the drip pan and on the interior surface of the door 6 trickles down 30 that surface to the drip edge 18 and being unable to creep along the under surface of the door 6 on account of the groove 17, will drip off of the edge 18 on to the sill 15. On account of the sloping contour of the sill 35 15, the water will drain therefrom inwardly into the compartment 2, the covering 16 being effective in preventing saturation of the wood or other material of which the casing may be constructed and consequent 40 rotting thereof. When the pan 7 is lowered for the removal of the container 3, the extension 8 provides for conducting the drippings caught by the pan to the interior of the refrigerator.

45 It is obvious that various changes may be made in details of construction without departing from the spirit of this invention; it is, therefore, to be understood that this invention is not to be limited to the specific 50 details shown and described.

Having thus described the invention, what is claimed is:

1. A show-case refrigerator having a compartment provided with a door-way 55 and a door therein, a refrigerant container in said compartment and having a metallic wall opposite but close to said door, said

container being constructed and positioned to cause circulation of air between said wall and said door, and a sill for said door-way 60 formed to direct condensed moisture into said compartment.

2. A show-case refrigerator having a compartment provided with a door-way and a door therein, a refrigerant container in said compartment and having a metallic wall opposite but close to said door, said container being constructed and positioned to cause circulation of air between said wall and said door, and a sill for said door-way 65 70 formed to direct condensed moisture into said compartment, said door having a drip edge above said sill.

3. A show-case refrigerator having a compartment provided with a door-way and a door therein, a refrigerant container in said compartment and opposite said door, means for guiding said container for movement into and out of said compartment, a drip receiving-pan mounted for movement beneath said container when out of said compartment and for movement into said door-way, and a sill for said door-way formed to direct condensed moisture into said compartment. 75 80 85

4. A show-case refrigerator having a compartment provided with a door-way and a door therein, a refrigerant container in said compartment and opposite said door, means for guiding said container for movement into and out of said compartment, a drip receiving-pan mounted for movement beneath said container when out of said compartment and for movement between said container and said door, and means for directing the condensed moisture into said compartment. 90 95

5. A show-case refrigerator having a compartment provided with a door-way and a door therein, a refrigerant container in said compartment and opposite said door, means for guiding said container for movement into and out of said compartment, a drip receiving-pan mounted for movement beneath said container when out of said compartment and constructed to drain into said compartment, said pan being movable into said door-way, and a sill for said door-way formed to direct condensed moisture into said compartment. 100 105 110

In testimony whereof I affix my signature this 9th day of November, 1921.

HARRY L. HUSSMANN.
